G. Kennedy

ATTORNEY

UNITED STATES PATENT OFFICE

LEO E. WOOD, OF CERRO GORDO, IOWA

SNOWPLOW

Application filed April 4, 1930. Serial No. 441,632.

My invention relates to improvements in snow removers, and the object of my improvement is to supply particularly for highway use, a snow plow of an improved and efficient shape for forward propulsion in gathering snow and delivering it obliquely laterally to a distance or beyond the road limits in dumping it to clear the way for traffic. Another improvement comprises mechanical means for vertically adjusting the plow with self-locking elements included, and a further improvement is in providing supporting runners for the plow when in use, to be tiltable in securing said vertical adjustments.

I have accomplished the above objects by the means which are hereinafter described and claimed, and which are illustrated in the accompanying drawings, in which Fig. 1 is a side elevation of my improved snow plow as attached to a propelling vehicle, parts of the latter being removed or broken away. Fig. 2 is a top plan of the same. Figs. 3 and 4 are respectively front and rear elevations of the snow plow as detached from said propelling means.

My invention is not restricted to the precise construction and arrangement of parts herein shown and described, nor to the various details thereof, as the same may be modified or rearranged in various particulars without departing from the spirit and scope of my invention, one practical embodiment of which has been herein illustrated and described without attempting to show all of the various forms and modifications in which my invention might be embodied.

My snow plow is shown as attached to the front part of a motor truck 17, whose mechanisms and some other parts have been removed for clearness and to present a conventional or diagrammatic elevation of said co-acting devices.

The plow is provided with a forwardly inclined and angularly diminished prow having the forwardly and laterally inclined plates 2 and a medial fin 3 leading to a medial forwardly curved part 9 whose concave forward angular edge has a vertical forwardly presented web-plate 10 presenting a longitudinal divisional wall at that location. The

side edges of the plates 2 have narrow and preferably sharpened margins 4 to thus better cut into crusts of drifts.

The side plates 2 are laterally bent upwardly into side walls 7 whose forward vertically disposed edges 8 may be slightly bent out of line as shown in Figs. 1 and 3, or may be continuous in one direction if preferred. These edges aid in gathering snow into the interspaces of the side walls 7 and the medial wall 10 thus providing a curvate bottom trough 6 on each side directed obliquely laterally and rearwardly past the forward part of the following truck 17, as best indicated in Fig. 2.

The plow 1 may when lowered to operating position be supported on small carrying wheels 5. The numeral 12 denotes a pair of spaced parallel sled runners whose rear parts are curved upwardly at 13 and pivotally mounted at 14 on the rear frame part 18 of the truck, the forward ends of the runners at 11 being bent vertically upward and fastened rigidly to the rear faces of the side walls 7 of the plow 1 between the truck 75

wheels.

A bracket structure is mounted rigidly on the rear part of the plow, comprising parallel vertical posts 15 connected across by bars 34 and 35 and the latter are connected by a vertical medial bar 36, as shown in Fig. 4.

Referring now to said Figs. 1 and 2, the numeral 24 denotes a rotatable transverse shaft mounted in the frame of the truck 17, and carrying a worm-wheel 26 also a transversely spaced pair of like sprocket-wheels 23, the worm-wheel intermeshing with a worm 29 on a worm-shaft 27 having a hand-wheel 28. Another and idler-shaft 20 is mounted in brackets at the front of the truck at 19 and carries a pair of sprocket-wheels 21 in forward alinement with the sprocket-wheels 23, and also carries an inner pair of grooved sheaves 22. On each side of the truck hood a chain of the open link type capable of lateral swinging has one end connected to a staple 32 at the top of the plow-bar 15, is carried thence under an idler sprocket 21 and rearwardly reeved over a sprocket 23 whence it is directed forwardly over an adja-

cent grooved sheave 22, thence forwardly and downwardly and including a tension spring 31 to be there connected to a staple or other fastening means 33 on the lower part of said 5 bar 15. The chain is thus kept under tension.

To lift the plow 1 clear of street or other obstructions while traveling to or from a district to be cleared of snow, the operator on the truck 17 may turn the hand-wheel 28 appropriately to cause the worm 29 to rotate the worm-wheel 26 and shaft 24, with its sprockets 23. The chains 30 are thus moved to lift the plow while causing its runners 12 to swing at their rear ends upwardly, thus clearing 10 the plow from the road surface to a desired distance, the self-locking worm and worm-wheel then locking the chains with the plow at an adjusted elevation. The operator reverses the above method, in order to lower 15 the plow to its working level. The runners 12 aid in carrying the plow over roughnesses in the way and take the load from the front of the truck, whose wheels may propel both the truck and plow at a desired speed ahead 20 to remove snow in their path.

The speed of the truck and plow may be regulated at will to handle snow of different consistencies, and ordinarily are driven at a considerable rate in order to cause gathered 25 snow to mount the side troughs 6 where it is slightly compressed because of the rearward convergence of the troughs, so that the traveling load is shot obliquely rearwardly to one side of a road with momentum enough 30 to deposit it on the right of way without the road surface, at least on one side. If the road is too wide to cause the snow to be shot to both sides in clearing the road, the apparatus may return along one side of the way 35 after clearing the other side part thereof. The medial wall 10 serves in completing the division between such side troughs and in the diversion of snow into the troughs, especially 40 while penetrating high drifts.

Having described my invention, what I claim as new, and desire to secure by Letters Patent, is:

A snow plow, a vehicle to which the plow is connected for vertical adjustments, and 50 mechanism mounted on said vehicle and connected to said plow for vertically adjusting it, comprising a rotatable transverse shaft on the vehicle having a worm-wheel thereon, a worm-shaft meshing therewith, a parallel rotatable shaft on the vehicle, said shafts having sprocket-wheels on their outer ends and the second-mentioned shaft having grooved sheaves thereon within its pair of sprocket-wheels, a pair of like chains each 55 having its ends connected respectively to an upper and lower part of the plow on one side thereof, the lower reach of the chain including an elastic element, one reach of each chain passing about both sprocket-wheels on its 60 side, thence around the sheave on that side.

and sled runners rigidly connected to the lower rear parts of the plow, extending rearwardly and having their rear ends bent upwardly toward and hinged to said vehicle.

In testimony whereof I affix my signature. 70
LEO E. WOOD.
